UNITED STATES PATENT OFFICE.

ALBERT VICKERS AND GEORGE THOMAS BUCKHAM, OF WESTMINSTER, LONDON,
ENGLAND, ASSIGNORS TO VICKERS LIMITED, OF WESTMINSTER, ENGLAND.

LOADING APPARATUS OF BREECH-LOADING GUNS.

1,128,555.

Specification of Letters Patent. Patented Feb. 16, 1915.

Application filed November 17, 1911. Serial No. 660,801.

To all whom it may concern:

Be it known that we, ALBERT VICKERS and GEORGE THOMAS BUCKHAM, both subjects of the King of Great Britain, residing at Vickers House, Broadway, Westminster, in the county of London, England, have invented 5 Relating to the Loading Apparatus of Breech-Loading Guns, of which the following is a specification.

This invention relates to the loading apparatus of breech loading guns and has particular reference to projectile trays of the kind that normally lie at one side of the gun 15 and that are adapted to move through an arc of a circle in a horizontal plane with the tray always parallel to the axis of the gun, so that the projectile is brought into the loading position behind the gun with its 20 nose within the breech opening.

According to this invention the projectile tray is pivotally mounted upon a supporting arm or member which in turn is pivotally connected to the cradle in such a manner 25 that it takes the weight of the tray and projectile so that the lever mechanism for keeping the tray parallel to the gun is not subjected to any load. As the said tray is not under the influence of the locking action of 30 the actuating worm gearing heretofore proposed we provide a catch device for normally retaining the said tray in the projectile receiving position. We may also provide means for insuring that when the breech 35 is closed the projectile tray shall occupy a position out of the path of recoil, these means preferably comprising an extension of the breech actuating hand lever adapted to bear against the inner surface of the 40 aforesaid supporting arm or member.

In order that the said invention may be clearly understood and readily carried into effect we will describe the same more fully with reference to the accompanying drawings in which:—

Figure 1 is a sectional side elevation, Fig. 2 a plan, and Fig. 3 an end elevation of the breech end of a gun provided with our improvements, the projectile tray being in its receiving position. Figs. 4 and 5 are respectively a vertical and a horizontal section of the breech end of the gun, showing the projectile tray in the loading position. Figs. 6 and 7 are views similar to Figs. 1

and 4 showing the telescopic form of tray, 55 which in Fig. 6 is adjusted to receive the projectile alone and in Fig. 7 is adjusted to receive the projectile and charge together. Fig. 8 is a section on an enlarged scale taken approximately on the line 1—1 of Fig. 6. 60 Fig. 9 is a section taken approximately on the line 2—2 of Fig. 8, and Fig. 10 is a transverse vertical section through the pivot of the projectile tray showing a method by which long and short trays are rendered in- 65 terchangeable.

In these figures A is the breech end of the gun, A' the breech chamber, A² the breech actuating hand lever and A³ the gun cradle.

B is the projectile tray.

C represents the aforesaid supporting arm or member which, in the examples shown, has a vertical pivot c adapted to fit in a socket d formed in a bracket D attached to the gun cradle. The said arm or member C is also provided with a socket C' adapted to receive the vertical pivot B' of the projectile tray B.

Pivots connected to the bracket D attached to the gun cradle are two horizontal 80 radius bars d', d² of equal length the points of connection of the said radius bars with the bracket being situated on stationary arms d'^x d^{2x} arranged on opposite sides of the aforesaid socket d. The free ends of 85 the radius bars d', d² are pivotally connected to the ends of a horizontal two armed lever or link b carried by the lower end of the aforesaid vertical pivot B' of the tray, about the axis of which pivot the tray turns in 90 order to maintain its parallelism in moving to and from the loading position.

The supporting arm C is furnished toward its rear end and on its inner surface with a stop c', which, when the tray B is swung into 95 the loading position, comes into contact with the breech face as clearly shown in Figs. 4, 5 and 7. The said supporting arm also has another stop C'^x which, by engaging with a part d^{xx} (Figs. 5 and 6) of the bracket D 100 on the cradle, limits the outward movement of the tray as shown in Fig. 2.

The aforesaid device for normally retaining the tray B in the projectile receiving position comprises in the examples shown a 105 catch b^{xx} (Figs. 2, 3 and 5) which is pivotally mounted in a socket forming part of the tray and which has a nose b^x adapted to en-

gage in a notch c^x in the supporting arm C; a handle B^x is attached to the tray adjacent to the catch b^x for moving the tray to and from its loading position.

- 5 The means for retaining the tray B out of the path of recoil of the gun when the breech is closed comprise, in the examples shown, an extension a^2 of the breech actuating hand lever A², which extension carries 10 a roller a^{2x} (Figs. 2 and 3). This roller, when the breech is closed, coöperates with the inner surface or edge C^o of the supporting arm C (as clearly shown in Fig. 2) to insure that the projectile tray B shall be 15 out of the path of recoil when said tray is in its receiving position, and shall remain in that position during the recoil owing to the fact that the aforesaid roller runs along the surface C^o during the recoil of the gun into 20 the position shown in dotted lines in Fig. 2.

The projectile tray is so constructed that when in its loading position it will enter the breech opening A' as shown in Figs. 4, 5 and 7 to a sufficient extent to protect 25 the breech threads from injury during the insertion of the projectile into the gun.

- In the example illustrated in Figs. 1 to 5 the projectile tray is adapted to receive the projectile only, but in the example shown in 30 Figs. 6 to 9, the tray is composed of two parts which are capable of relative longitudinal or telescopic movement so that the tray can be lengthened to adapt it to receive the projectile and the powder charge (as 35 shown in Fig. 7) and shortened to receive the projectile only as shown in Fig. 6. In order to retain the parts in their adjusted position a clamping bolt E (Figs. 8 and 9) is provided which is under the control of a 40 flat spring e normally tending to keep the bolt E in engagement with holes in the two parts of the tray. A handle E^x is attached to the bolt E for actuating it. When provision is made for interchanging long and 45 short trays, each of the trays is formed with a vertical pin B^o (Fig. 10) which fits into a hole in the aforesaid vertical pivot B' carried in the socket C' of the supporting arm C. The pin B^o and pivot B' are preferably 50 clamped together by a spring controlled bolt b^o which passes through the pivot B' and engages in a recess in the pin B^o.

What we claim and desire to secure by Letters Patent of the United States is:—

- 55 1. In loading apparatus for ordnance, the combination of a loading tray adapted to lie to one side of the gun and to be swung into the loading position behind the gun with the nose of the projectile within the breech opening, a member pivoted to the gun cradle for supporting the whole weight of the tray and projectile, means for pivotally superposing the tray upon said member, lever mechanism for keeping said tray 60 parallel to the gun during its swinging

movements to and from the loading position, and a handle on said tray for effecting a direct manual movement thereof.

2. In loading apparatus for ordnance, the combination of a loading tray adapted to lie to one side of the gun and to be swung into the loading position behind the gun with its front portion and the nose of the projectile within the breech opening, a pivoted member for supporting the whole weight of the tray and projectile, means for pivotally superposing the tray upon said member, lever mechanism for keeping said tray parallel to the gun during its swinging movements to and from the loading position, and a handle on said tray for effecting a direct manual movement thereof.

3. In loading apparatus for ordnance, the combination with the gun cradle, of a loading tray adapted to lie to one side of the gun and to be swung into the loading position behind the gun with its front portion and the nose of the projectile within the breech opening, a member pivoted to the gun cradle at a point behind and to one side of the gun breech and adapted to support the whole weight of the tray and projectile, means for pivotally superposing the tray upon said member, lever mechanism for keeping said tray parallel to the gun during its swinging movements to and from the loading position, and a handle on said tray for effecting a direct manual movement thereof.

4. In loading apparatus for ordnance, the combination with the gun cradle, of a loading tray adapted to lie to one side of the gun and to be swung into the loading position behind the gun with its front portion and the nose of the projectile within the breech opening, a member pivoted to the gun cradle at a point behind and to one side of the gun breech and adapted to support the whole weight of the tray and projectile, means for pivotally superposing the tray upon said member, lever mechanism for keeping said tray parallel to the gun during its swinging movements to and from the loading position, and a handle on said tray for effecting a direct manual movement thereof.

5. In loading apparatus for ordnance, the combination with the gun cradle, of a loading tray adapted to lie to one side of the gun and to be swung into the loading position behind the gun with its front portion and the nose of the projectile within the breech opening, a member pivoted to the gun cradle at a point behind and to one side of the gun breech and adapted to support the whole weight of the tray and projectile, a downwardly projecting pivot on said tray, a boss on said member provided with a socket for said pivot, lever mechanism for keeping said tray parallel to the gun during its swinging movements

to and from the loading position, and a handle on said tray for effecting a direct manual movement thereof.

6. In loading apparatus for ordnance, the combination with the gun cradle, of a loading tray adapted to lie to one side of the gun and to be swung into the loading position behind the gun with its front portion and the nose of the projectile within the breech opening, a member pivoted to the gun cradle at a point behind and to one side of the gun breech and adapted to support the whole weight of the tray and projectile, a downwardly projecting pivot on said tray, a boss on said member provided with a socket for said pivot, a two armed lever on said pivot, parallel levers connecting the ends of said levers to the gun cradle for keeping the tray parallel to the gun during its swinging movements to and from the loading position, and a handle on said tray for effecting a direct manual movement thereof.

7. In loading apparatus for ordnance, the combination with the gun cradle, of a bracket attached to the cradle and extending to the rear of the gun breech, a loading tray adapted to lie to one side of the gun and to be swung into the loading position behind the gun with its front portion and the nose of the projectile within the breech opening, a member for supporting the whole weight of the tray and projectile, a downwardly projecting pivot on said member fitting in a socket in the aforesaid bracket said socket being behind and to one side of the gun breech, a downwardly projecting pivot on said tray, a boss on said member provided with a socket for said pivot, a two armed lever on said pivot, parallel levers connecting the ends of said lever to the said bracket for keeping the tray parallel to the gun during its swinging movements to and from the loading position, and a handle on said tray for effecting a direct manual movement thereof.

8. In loading apparatus for ordnance, the combination with the gun cradle, of a loading tray adapted to lie to one side of the gun and to be swung into the loading position behind the gun with its front portion and the nose of the projectile within the breech opening, a member pivoted to the gun cradle at a point behind and to one side of the gun breech and adapted to support the whole weight of the tray and projectile, means for pivotally superposing the

tray upon said member, lever mechanism for keeping said tray parallel to the gun during its swinging movements to and from the loading position, a handle on said tray, and a catch device adjacent to said handle for coöperating with the said member.

9. In loading apparatus for ordnance, the combination with the gun cradle, of a loading tray adapted to lie to one side of the gun and to be swung into the loading position behind the gun with its front portion and the nose of the projectile within the breech opening, a member pivoted to the gun cradle at a point behind and to one side of the gun breech and adapted to support the whole weight of the tray and projectile, means for pivotally superposing the tray upon said member, lever mechanism for keeping said tray parallel to the gun during its swinging movements to and from the loading position, a handle on said tray, and a catch device carried by the tray for coöperating with said member.

10. In loading apparatus for ordnance, the combination with the breech actuating mechanism, of a loading tray adapted to lie to one side of the gun and to be swung into the loading position behind the gun with the nose of the projectile within the breech opening, a hand lever for operating said breech mechanism, and a device forming part of said hand lever for insuring that when the breech is closed the tray shall occupy a position out of the path of recoil of the gun.

11. In loading apparatus for ordnance, the combination with the breech actuating mechanism and the gun cradle, of a loading tray adapted to lie to one side of the gun and to be swung into the loading position behind the gun with the nose of the projectile within the breech opening, a hand lever for operating said breech actuating mechanism, a member pivoted to the gun cradle and adapted to support the whole weight of the tray and projectile, an extension of said hand lever adapted to engage with the inner surface of said member, and stops carried by said member for limiting the movements of the tray.

In testimony whereof we affix our signatures in presence of two witnesses.
